UNITED STATES PATENT OFFICE.

HERBERT H. STEELE, OF MARCELLUS, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,023,891.

Specification of Letters Patent. Patented Apr. 23, 1912.

Application filed November 6, 1909. Serial No. 526,560.

To all whom it may concern:

Be it known that I, HERBERT H. STEELE, a citizen of the United States, and resident of Marcellus, in the county of Onondaga 5 and State of New York, have invented certain new and useful Improvements in Type-Writing Machines, of which the following is a specification.

My invention relates to paper feeding 10 mechanism for typewriting machines and its general object is to provide improved mechanism of the class stated.

To the above and other ends which will hereinafter appear, my invention consists in 15 the features of construction, arrangements of parts and combinations of devices to be hereinafter described and particularly pointed out in the claims.

My invention has been embodied in mechanism which is especially adapted to controlling a plurality of sheets of paper arranged side by side on a single platen, and comprises means for feeding the sheets 20 separately and also for holding or clamping one of the sheets while another of the sheets is being fed, the feeding and controlling 25 means for the two sheets being entirely distinct and independently operated.

My improved paper feeding and controlling mechanism may be so regulated that if desired a plurality of sheets may be fed together; and said mechanism is further adapted to feed singly wide sheets extending substantially throughout the full length 35 of the platen.

The invention is shown applied to a long platen of the kind employed in the Monarch typewriting machine but the nature of the invention is such that it may readily be 40 adapted in whole or in part to other styles of writing machine platens and platen carriages.

In the accompanying drawings, Figures 1 and 2 are fragmentary plan views of opposite end portions of a platen carriage and platen embodying my invention, parts associated with said carriage and not necessary to a complete understanding of said invention being omitted. Fig. 3 is an end view 45 of the carriage. Fig. 4 is a view corresponding to Fig. 3 but showing some of the parts in different relations and omitting other parts. Fig. 5 is an end view of a detail of my invention. Fig. 6 is a plan view 50 of a carriage embodying a modification of

my invention. Fig. 7 is a fragmentary detail plan view of a further modification.

The form of the invention shown in Figs. 1 to 5 will first be described. As shown in Figs. 1 to 3, grooved track-ways 1 are fixed 60 on the frame of the machine, said track-ways receiving anti-friction balls 2 which co-operate with a grooved slide bar 3 comprised in a platen frame, carrier or carriage which further includes end bars 4. Mounted in 65 the carrier is a platen 5 which is equipped with the usual step-by-step line feeding devices, including a ratchet wheel 6 connected with one end of said platen. The platen is or may be of the style known as a long or 70 wide platen and is preferably equipped with two sets of the usual feed or pressure rollers, the support for each set comprising a pair of lugs or brackets 7 projecting forward from the slide bar 3. Pivoted at 8 in 75 each bracket is an arm 9, the arms forming two pairs and each pair of arms supporting a shaft 10 carrying the sections 11 of a main feed roller which is constantly pressed toward the platen by springs 9^a coöoperating 80 with the arms 9. Pivoted at 12 to each bracket 7 is an arm 13, each pair of arms 13 supporting a shaft 14 whereon are sections 15 of a secondary feed roller which is constantly pressed toward the platen by 85 springs 16. The platen is provided at each end with a spring-pressed paper apron or deflector 17 of the usual construction.

It will be understood from what has been said of Figs. 1 and 2 that there are two sets of main and two sets of secondary feed rollers, one set of each being associated in the usual way and arranged to coöperate with one end or half of the platen. By means 90 of each set of main feed or pressure rolls and the associate set of secondary rollers, together with the paper deflector through which the rollers coöperate with the platen, a sheet may be fed around each end of the platen toward the printing point. 100

Each set of paper feeding and controlling devices, comprising main and secondary feed rollers and paper deflector, is provided with releasing means, the releasing means for the left-hand set being controlled by devices mounted outside the left-hand end bar 4, while the releasing means for the right-hand set are controlled by devices mounted outside the right-hand end bar 4. Each releasing means comprise a rock shaft 18 hav- 110

ing bearings in a pair of the brackets 7. The rock shaft has projections or lugs 19 which coöperate with lugs 20 on the arms 9 to throw off or release the main feed roller, 5 and through said arms to release the secondary feed roller and the paper deflector, when the rock shaft is turned. The means for turning the rock shaft may be that shown in the pending application of Edwin 10 E. Barney, Serial No. 403,531, filed November 23rd, 1907 and which comprises an arm 21 secured by a screw 22 to the rock shaft, said arm being actuated by an arm 23 pivoted to the arm 21 at 24 and provided with 15 a finger piece 25, said arm 23 being pivoted at 26 to an arm 27 pivoted at 28 to the adjacent end bar 4.

The normal position of the parts constituting the releasing means appears in Fig. 20 3. When the finger piece 25 is pulled forward to the Fig. 4 position the toggle composed of the arms 27 and 23 is straightened, locking the parts in the Fig. 4 position. During the movement of the parts from the 25 Fig. 3 to the Fig. 4 position the rock shaft 18 is rocked, causing the lugs 19 to act on the lugs 20, swinging the arms 9 downward and rearward to release the main feed roller, said arms 9 acting against the arms 13 to release the secondary feed roller and the paper 30 deflector.

A rod 29 arranged above the platen and extending lengthwise thereof is secured at its ends to the end bars 4, said rod supporting paper fingers which may be of the usual 35 Monarch pattern comprising each a hub 30 engaging the rod 29, an arm 31 curving forward over the platen from the hub 30 and carrying a spring pressed guide finger 32 40 and also carrying a roll carrier 33 pivoted at 34 and supporting a pressure roll 35 which coöperates with the platen through an opening in the guide finger 32. As shown in Fig. 3 the carrier 33 provides a bearing for 45 a spring plunger 36, the hub whereof co- 50 operates with cam faces 37^a on the arm 31 to maintain the roll 35 in or out of operation. In the present instance four paper 55 fingers are mounted on the rod 29 and arranged in pairs one pair operating to guide and control the work sheet at the left as it passes above the printing line up over the platen from the left-hand set of paper feeding and controlling devices heretofore de- 60 scribed which guide said sheet from the introductory side of the platen around and under the same to within a short distance of the printing line at the front of the platen. The right-hand pair of paper 65 fingers coöperate with the right-hand work sheet. As ordinarily constructed the paper fingers are slidable along the supporting rod 29 but in the present instance said paper fingers are preferably fixed on said rod as by pins 37 which pass through the hubs 30 and

rod 29 and secure their respective paper fingers in position to coöperate with the side margins of the work sheets. An erasing plate or shelf 38 is mounted on the rod 29 in the usual or any suitable way and extends substantially throughout the length of the platen, said erasing plate underlying the arms 31 and inclining downward and forward from the rod 29 over the platen and to within a very short distance of the surface 75 thereof.

Referring now to the novel devices to which my invention more particularly relates, these comprise in the Figs. 1-5 construction a plurality of clamping or gripping elements which coöperate with the right-hand end portion of the erasing plate 80 38 to grip the paper and are automatically controlled by the right-hand releasing means operated from the right-hand finger piece 85 25, said finger piece also operating to throw off the two right-hand pressure rolls 35 at the same time that it releases or throws off the right-hand main and secondary feed rollers. To provide a support for the clamping 90 elements the right-hand pair of paper fingers are provided with hubs or collars 39 integral with the arms 31 and at the upper sides of the same and near the forward ends. These hubs provide bearings for a rock shaft 95 40, said rock shaft extending parallel with the rod 29 and being arranged forward of the same and above the platen. The clamping elements or gripping fingers may be separate pieces but as herein shown are part 100 of a clamping member 41 preferably formed of sheet metal and supported on the rock shaft 40. Said clamping element comprises a plurality of parallel spring fingers 42 which curve downward and rearward over the erasing shelf 38, five fingers or clamps 42 being shown in the present instance. The member 41 further comprises portions 43 which are curled around the rock shaft 40 and receive pins 44 which hold the member 41 in fixed relationship with the shaft 40. Each of the fingers 42 is provided preferably with a sheath 45 of rubber or the like so as to improve and facilitate the gripping or clamping co-action between said fingers and the erasing plate. At its left-hand end the rock shaft 40 projects beyond the hub or bearing 39 to receive a forwardly extending crank arm 46, said crank arm being provided with a hub 47 which is secured by a set screw 48 to the rock shaft. The right-hand end of the rock shaft 40 extends outward beyond its bearing 39 to provide a support for a lever 49, said lever having a collar 50 in which is threaded a set screw 50^a 110 for fixing the lever to the rock shaft. The forward arm of the lever 49 corresponds to the crank arm 46. The rear arm of the lever 49, as best appears in Figs. 3 and 4, 115 extends backward above the platen, and its 120 125 pins 51 which pass through the hubs 30 and

rear end pivotally supports at 51 a depending link 52 the lower end whereof is pivotally connected at 53 with a crank arm 54 projecting forward from the right-hand releasing rock-shaft 18. As shown in Fig. 1 the crank arm 54 is provided with a hub 55 which surrounds said rock shaft 18 and receives a securing screw 56.

It will be understood that the connections between the rock shafts 18 and 40, which connections comprise the crank arm 54, link 52 and lever 49, will transmit rotary movement from the rock shaft 18 to the rock shaft 40 so that when the rock shaft 18 is rocked the rock shaft 40 will be rocked oppositely to corresponding extents. Further it will be apparent that the rocking movement of the rock shaft 40 will cause the clamping fingers 42 to be swung into and out of clamping engagement with the erasing plate. In order to control the right-hand pressure rolls 35 from the right-hand finger piece 25, the carriers 33 of the right-hand pair of paper fingers are provided each with a laterally extending pin 57 which enters an enlarged circular opening 58, the left-hand opening 58 being formed at the forward end of the crank arm 46 and the right-hand opening 58 in the forward arm of the lever 49. After the rock shaft 40 has turned some distance from normal position the edges of the openings 58 will engage the pins 57 and swing the pressure rolls away from the platen, said pressure rolls being locked out by the spring plunger 36 in the usual way. The lost motion between the openings 58 and pins 57 is employed owing to the different extents to which the rock shaft 40 and the roll carrier 33 may be moved.

Comparing Figs. 3 and 4 it will be seen that in the normal or Fig. 3 position there is a considerable space provided for the paper between the clamping fingers 42 and the erasing plate 38 so that the paper may be fed, by coöperation between the platen and the various controlling devices which are operative in Fig. 3, rearward over the erasing plate and between it and the clamping fingers. When the finger piece 25 is pulled forward to the Fig. 4 position it operates to turn the rock shaft 18 forward and to throw off or release the main and secondary feed rollers as has been heretofore explained. The forward turning of the rock shaft 18 operates through the connections with the rock shaft 40 to turn said rock shaft rearward and throw the clamping fingers 42 down into engagement with the erasing shelf. The clamping fingers being of spring metal are adapted to yield so as to insure that each shall coöperate with the erasing plate to clamp the paper thereagainst. Simultaneously with the throw-off of the feed rollers and the engage-

ment of the clamping fingers, the crank arm 46 and the forward arm of the lever 49 will be swung upward, operating through the pin and hole connection 57-58 to swing the pressure rolls 35 upward away from the platen to the released position shown in Fig. 4. It will be apparent from a consideration of Fig. 4 that when the parts are held or set as therein illustrated the feed rollers and pressure rolls will be inoperative on the paper and the paper will be clamped by the fingers 42 so that it cannot be fed or advanced when the platen is turned.

My invention as hereinbefore described is particularly adapted to "detail and summary" work in connection with way bills, in which character of work two work sheets are employed, said sheets being arranged side by side on the platen. The way bills may be copied *in extenso* one after another on the work sheet at the left-hand side of the platen, while the right-hand work sheet is adapted to receive only the totals of the way bills in condensed order. It will be understood that in work of this character a way bill may occupy any number of lines on the left-hand sheet depending on the number of items on the bill, and that said sheet must be correspondingly line spaced a plurality of times. Further it will be understood that during the printing and spacing operations on the left-hand sheet while the items on a way bill are being copied, the right-hand sheet is neither printed on nor advanced. To obtain these results the left-hand set of paper feeding and controlling devices, including the left-hand main and secondary feed rollers and the left-hand pair of pressure rolls, coöperate with the platen to control and feed the left-hand or detail sheet; while at the same time the right-hand set of paper controlling devices are in the Fig. 4 position, the feed and pressure rollers being released and inoperative and the clamping fingers 42 coöperating with the erasing shelf to clamp or grip the right-hand or "summary" sheet and prevent its being advanced when the platen is turned. When the last item on the way bill has been copied on the detail sheet and said sheet is advanced for receiving the line of totals of said way bill, then the right-hand finger piece 25 is pushed back to the Fig. 3 position, releasing the clamps 42 and bringing the right-hand feed and pressure rollers into operation. After the totals have been printed on the detail sheet the platen is moved leftward until the "summary" or the right-hand sheet is brought opposite the printing point, whereupon the totals are repeated on the right-hand sheet. Thereafter the platen is line spaced in the usual way, advancing both the left-hand and right-hand sheets together, after which the right-hand finger piece 25 is pulled for-

ward, restoring the clamping fingers 42 to operative position against the "summary" sheet and releasing the right-hand feed and pressure rollers, thus re-setting the mechanism so that the next succeeding way bill may be copied and summarized in the way above described. It will be understood that the lines of totals, one for each way bill are written in condensed form on the right-hand or "summary" sheet so that said sheet will serve for summarizing a large number of way bills which may fill a plurality of "detail" sheets. According to the system in vogue in the business for which my improvements as herein illustrated were designed, the left-hand or detail sheets are filed for reference while the condensed records or summaries are forwarded to the auditor of the concern.

It will be clear that my improvements may be used in other ways besides that described, and that as has been stated they may be employed with single wide sheets extending substantially throughout the full width of the platen. Further it will be understood that various changes may be resorted to without departing from my invention. An example of such changes is illustrated in Fig. 6 wherein two sets of clamping devices each comprising a plurality of clamping fingers 42 are provided, one set coöperating with the work sheet *a* at the left-hand side and the other set with the work sheet *b* at the right-hand side. These two sets are or may be similar in all respects to the set first described and may be similarly operated, the left-hand finger piece 25 controlling the left-hand clamping fingers and pressure rolls through connections which are duplicates of those at the right-hand side and such as have been described above in detail. When a construction like that shown in Fig. 6 is employed, either of the work sheets *a* or *b* may be advanced separately line by line to any desired extent while the other of the sheets is held clamped by the opposite set of fingers 42 to the associate portion of the erasing plate 38, so that the clamped sheet is held positively from being advanced when the platen is turned for line spacing the first sheet.

A further modification relating to a detail of construction is illustrated in Fig. 7 which shows a fragmentary portion of an erasing plate or shelf 59 which is formed at suitable intervals with pairs of parallel kerfs or slots 60, each pair of kerfs providing between them a tongue 61 which receives and is covered by a sheath 62 of rubber or the like. It will be understood that one of these sheathed tongues is to be arranged opposite each of the clamping fingers, so that each clamping finger will coöperate with one of the sheathed tongues. In the Fig. 7 construction the sheath 45 with which the

clamping fingers of the first described constructions were provided may be dispensed with.

I do not claim herein a means for releasing and throwing on two sets of feed rollers in alternation. It will be observed that by my present invention I provide various devices or means for controlling paper or work sheets, certain of these devices or means co-operating with the platen to feed paper when the platen is turned, certain other of said devices or means clamping paper and preventing its advancement; that there are provided in combination with a platen, a plurality of sets of paper feeding devices coöperative with the platen to feed paper and arranged side by side lengthwise of the platen, and means for separately controlling said devices; that a plurality of sets of paper controlling devices are provided, one set for each of a plurality of work sheets, in combination with means for separately controlling said sets of devices; that sets of paper feeding devices are combined with means for moving one of said sets into and out of coöperation with the platen while another of said sets remains in coöperation with said platen; that means are provided for moving one set of paper controlling devices into and out of operative position without affecting another of said sets; that sets of paper controlling devices are combined with hand operated actuators, including in the present instance the finger pieces 25, each actuator being connected with only one set of paper controlling devices; that said actuators are independent of each other; that means are provided for feeding paper at or near one end, side or half of the platen, while separately controlled means for feeding paper are provided at the other end, side or half of the platen, both said means coöperating directly with the platen; that a feed roller coöperates with the platen near one end, a second feed roller coöperating with the platen near its opposite end, means being provided for independently releasing said feed rollers; that means are arranged near one end of a platen for controlling a work sheet at opposite sides of the printing line, associated with a set of devices for moving said means into and out of operation, other controlling means at the opposite end of the platen being adapted to coöperate with a work sheet above and below the printing line, said other controlling means being movable into and out of operation by a second set of devices; that said sets of devices last above referred to are independently operative; that there is provided in association with the platen of a front-strike typewriting machine, feeding means coöperative with the platen near one end for controlling the paper above and below the printing line, devices for moving said means into and out of operation, 130

other feeding means coöperative with the platen near its opposite end for controlling paper above and below the printing line, and devices for moving said other feeding means into and out of operation, the moving devices for one feeding means being independent of the moving devices for the other feeding means; that there is provided in combination a platen, paper feeding mechanism 10 and separately controlled paper clamping mechanism; that in the present instance said paper feeding mechanism comprises certain rollers and rolls and said paper clamping mechanism comprises certain spring clamping fingers and a coöperating abutment, shelf or erasing plate; that mechanism for feeding one sheet of paper is combined with a clamp for another sheet of paper and means for independently controlling said feeding 15 mechanism and said clamp; that means coöperate with a platen for feeding paper, said means being combined with a clamp independent of the platen but controllable concurrently with said means; that means are 20 also provided for controlling paper, said means in the present instance being at the opposite end of the platen from the paper clamp, means being provided for separately controlling said last named paper feeding 25 means and said clamp; that paper feeding means coöperate with the platen at opposite sides of the printing line thereon in combination with a paper clamp at one side of the printing line and means for simultaneously 30 or concurrently controlling said feeding means and said clamp; that in the present instance, controlling means operate to release the paper feeding means and concurrently bring the clamp into operation; that 35 40 in the present instance the clamp and the paper feeding means are brought into operation alternately, the paper feeding means referred to being that which is at the same end of the platen as the clamp; that a paper finger device is provided comprising a pressure roll mounted on a carrier pivoted on a rigid support, said device being mounted on a rod which is fixed to the platen carrier; that in the present instance the pressure rolls 45 50 coöperate with the platen above the printing line; that means are provided for releasing the spring pressed feed roller at the under side of the platen and for concurrently swinging the pressure roll carriers to release 55 the pressure rolls; that I employ a clamping mechanism comprising a clamping finger having a removable sheath, the sheath in the present instance being preferably of rubber composition or the like; that a hand controlled clamping element or finger is provided on the platen carrier; that a coöperative clamping element, abutment or erasing 60 plate is provided; that the clamping elements are independent of the platen; that a 65 sheath of rubber or the like is arranged on

one of said clamping elements; that a hand controlled clamp coöperates with an abutment on the platen carrier; that in the present instance the abutment extends lengthwise of the platen, and the hand controlled clamp comprises a plurality of pivoted clamping fingers; that two relatively movable clamping elements are combined with means for locking said elements in clamping relationship; and that various other combinations are provided, some of which are set forth in the following claims.

It will be understood that various changes besides those above described may be made without departing from my invention.

What I claim as new and desire to secure by Letters Patent, is:—

1. In a typewriting machine, the combination of a single platen, a plurality of paper feeding devices for feeding sheets of paper separately or together, said sheets being arranged side by side at opposite end portions of the same platen, said devices coöperating with opposite end portions of the platen at the introductory side thereof, and means for separately controlling said devices.

2. In a typewriting machine, the combination of a single platen, a plurality of paper controlling devices, each coöperative with the platen to control a work sheet at the introductory side of the platen, and means for separately controlling said devices so that each may co-act directly with the platen to control its sheet independently, each of the work sheets either advancing with the platen when the platen is turned or else lying quiescent against the platen during the turning thereof.

3. In a typewriting machine, the combination of a single platen, two sets of paper feeding devices, each coöperative with the said platen, and separate moving means for each set, each moving means being controlled by a single key which is operative to move the associate set as a whole into and out of coöperation with the platen while the other set remains in coöperation with the platen.

4. In a typewriting machine, the combination of a single platen, two paper controlling devices each for controlling a separate sheet at the introductory side of the said platen, and means for moving either one of said devices into and out of operative position independently of the other device, so that either one of said work sheets may advance as the platen is turned while the other work sheet lies quiescent against said platen during the turning of the same.

5. In a typewriting machine, the combination of a single platen, two paper controlling devices, each for controlling a separate sheet at the introductory side of the platen, and hand operated actuators each connected with one of said devices and operative thereon so that either one of the work sheets

may be fed with the platen when it is turned while the other work sheet remains quiescent against said platen during the turning of the latter.

5. In a typewriting machine, the combination of a single platen, two paper feeding devices, each adapted to feed a separate sheet at the introductory side of the platen, and hand controlled actuators each connected 10 with one only of said devices, said actuators being independent of each other and operative on said devices so that either one of the sheets may be fed with the platen during the turning thereof while the other sheet remains quiescent against the platen as it is turned.

7. In a typewriting machine, the combination of a single platen, means for feeding paper at one end of said platen, and separately controlled means for feeding a different sheet of paper at the other end of said platen, both of said means coöperating directly with the platen at its introductory side to feed the separate sheets thereover at 25 different times and so that either one of the sheets may lie quiescent against the platen while said platen is being turned to feed the other sheet.

8. In a typewriting machine, the combination of a single platen, a feed roller coöperative with the platen near one end, a second feed roller coöperative with the platen near its opposite end, keys mounted on the platen frame, and means operative by said 35 keys for independently releasing and rendering operative said feed rollers, the feed rollers being thus controllable to permit the platen to be turned to feed either one of two sheets while at the same time the other sheet extending around the said platen remains quiescent.

9. In a typewriting machine, the combination of a platen, means arranged near one end thereof for controlling a work sheet at 45 opposite sides of the printing line, a set of devices for moving said means into and out of operation, other controlling means at the opposite end of the platen for controlling a work sheet at opposite sides of the printing line, and a second set of devices for moving said other controlling means into and out of operation.

10. In a typewriting machine, the combination of a platen, means arranged near one 55 end thereof for controlling a work sheet at opposite sides of the printing line, a set of devices for moving said means into and out of operation, other controlling means at the opposite end of the platen for controlling a work sheet at opposite sides of the printing line, and a second set of devices for moving said other controlling means into and out of operation, said sets of devices being independently operative.

65. 11. In a typewriting machine, the combi-

nation of a platen, feeding means coöperative therewith near one end for engaging the paper at opposite sides of the printing line, devices for moving said means toward and away from the platen, other feeding means coöperative with the platen near its opposite end for engaging the paper at opposite sides of the printing line, and devices for moving said other feeding means toward and away from the platen, the devices at opposite ends of the platen being independent of each other.

70. 12. In a front strike typewriting machine, the combination of a platen, feeding means coöperative therewith near one end for controlling paper above and below the printing line, devices for moving said means into and out of operation, other feeding means coöperative with the platen near its opposite end for controlling paper above and below the printing line, and devices for moving said other feeding means into and out of operation, the moving devices for one feeding means being independent of the moving devices for the other 75 feeding means.

80. 13. In a typewriting machine, the combination of a platen, paper feeding mechanism coöperative with a sheet at one end of the platen, and separately controlled 85 paper clamping mechanism for holding a second sheet from being fed, said second sheet being arranged at the opposite end of the platen and side by side with the first sheet.

85. 14. In a typewriting machine, the combination of a platen, mechanism for feeding one sheet of paper, a clamp for holding another sheet of paper against movement when the platen is turned, and means for 90 independently controlling said feeding mechanism and said clamp.

95. 15. In a typewriting machine, the combination of a platen, means coöperative therewith for feeding paper, and a paper clamp 100 independent of the platen and controlled concurrently with said means.

105. 16. In a typewriting machine, the combination of a platen, means coöperative therewith for feeding a sheet arranged near one end of the platen, a paper clamp independent of the platen and coöperative with a sheet arranged near the opposite end of the platen and side by side with the first sheet, and means for separately controlling said 115 first recited means and said paper clamp.

120. 17. In a typewriting machine, the combination of a platen, means for feeding paper at one end thereof, and means for positively clamping paper at the opposite end thereof to prevent the clamped paper from being fed when the platen is turned.

125. 18. In a typewriting machine, the combination of a platen, means for feeding paper at one end thereof, and means for clamp 130

ing paper at the opposite end thereof, the feeding means coöperating with said platen and the clamping means being independent of said platen.

5 19. In a typewriting machine, the combination of a platen, means coöperative therewith at opposite sides of the printing line for feeding paper, a paper clamp at one side of the printing line, and means for simultaneously controlling said feeding means and said clamp.

10 20. In a typewriting machine, the combination of a platen, means coöperative therewith at opposite sides of the printing line for feeding paper, a paper clamp at one side of the printing line, and means for releasing said feeding means and concurrently bringing said clamp into operation.

15 21. In a typewriting machine, the combination of a platen, means coöperative therewith at opposite sides of the printing line for feeding paper, a paper clamp at one side of the printing line, and means for simultaneously controlling said feeding means and said clamp to bring them into operation alternately.

20 22. In a typewriting machine, the combination of a platen, a platen carrier, a feed roller at one side of the printing line, a rod fixed to the platen carrier, a paper finger device on said rod, said paper finger device comprising a guide finger and a pressure roll, and means for releasing said roller and simultaneously releasing said roll independently of said guide finger.

25 23. In a front strike typewriting machine, the combination of a platen carrier, a platen thereon, a feed roller extending lengthwise of the platen below the printing line, a support fixed to the platen carrier and extending lengthwise thereof, paper finger devices on said support and comprising pivoted carriers and pressure rolls carried thereon, said pressure rolls coöperating with the platen above the printing line, and means for releasing said feed roller and for concurrently swinging said carriers to release said pressure rolls.

30 24. In a typewriting machine, the combination of a platen carrier, a platen thereon, a spring pressed feed roller, means for releasing said feed roller comprising a hand controlled rock shaft, a paper finger device comprising a rigid support, a pressure roll pivoted thereon and a guide finger, and connections between said rock shaft and said pressure roll for concurrently releasing said pressure roll independently of said guide finger when said feed roller is released.

35 25. In a typewriting machine, the combination of a platen carrier, a platen thereon, a spring pressed feed roller, means for releasing said feed roller comprising a hand controlled rock shaft, a paper finger device comprising a rigid support and a pressure

roll pivoted thereon, and connections between said rock shaft and said pressure roll, said connections comprising a crank arm fixed to said rock shaft, a lever connected with said pressure roll and a link connecting said lever and said crank arm.

40 26. In a typewriting machine, the combination of a platen carrier, a platen thereon, a hand controlled clamping element or finger on said platen carrier, a coöperative clamping element or abutment, and a sheath of rubber or the like on one of said clamping elements.

45 27. In a typewriting machine, the combination of a platen carrier, a platen thereon, an abutment on said platen carrier, and a hand controlled clamp coöperative with said abutment.

50 28. In a typewriting machine, the combination of a platen carrier, a platen thereon, an abutment on said platen carrier extending lengthwise of the platen, and a plurality of pivoted hand controlled clamping fingers coöperative with said abutment.

55 29. In a typewriting machine, the combination of a platen carrier, a platen thereon, an abutment on said platen carrier extending lengthwise of the platen, a plurality of pivoted hand controlled clamping fingers coöperative with said abutment, a feed roller, means for releasing said feed roller, and connections between said feed roller and said clamping fingers.

60 30. In a typewriting machine, the combination of a platen carrier, a platen thereon, an erasing plate, and a pivoted hand controlled clamping device coöperative with said plate.

65 31. In a typewriting machine, the combination of a platen carrier, a platen thereon, an erasing plate on said platen carrier, a hand controlled rock shaft on said platen carrier, and a plurality of spring fingers on said rock shaft, said fingers coöperative with said plate to clamp paper.

70 32. In a typewriting machine, the combination of a platen, a feed roller, a clamping finger, a coöperative abutment, and means for releasing said feed roller and locking it in released position and for concurrently moving said clamping finger to clamping position and locking it.

75 33. In a typewriting machine, the combination of a platen, relatively movable clamping elements, and means separated from the clamping elements proper and arranged outside the platen for positively locking said elements in clamping relationship.

80 34. In a typewriting machine, the combination of a platen, two relatively movable clamping elements, and means for moving one of said elements into coöperation with the other element and there locking said movable element, the devices by which the

movable element is locked being separated from said movable element and arranged outside the platen.

35. In a front strike typewriting machine, 5 the combination of a platen, a feed roller below the printing line, pressure rolls above the printing line, clamping fingers above the printing line, and hand controlled means for moving said feed roller, said pressure

10 rollers and said clamping fingers.

36. In a typewriting machine, the combination of a platen carrier, a platen thereon, a paper finger rod on said platen carrier, paper finger devices on said rod, a support 15 on said paper finger devices, clamping fingers on said support, and manual means connected with said support.

37. In a front strike typewriting machine, 20 the combination of a platen carrier, a platen thereon, a paper finger rod on said platen carrier, paper finger devices on said rod, a support on said paper finger devices, clamping fingers on said support, a feed roller, means for releasing said feed roller, 25 comprising a rock shaft, and connections between said rock shaft and said support.

38. In a typewriting machine, the combination of a platen carrier, a platen thereon, a feed roller, means for releasing the same

comprising a hand controlled shaft, a paper 30 finger rod, paper finger devices thereon comprising rolls, an erasing plate, a rock shaft on said paper finger devices, clamping fingers on said rock shaft and coöperative with said erasing plate, and connections be- 35 tween said rolls, said rock shaft and said hand controlled shaft.

39. In a typewriting machine, the combination of a platen carrier, a platen thereon, a feed roller, means for releasing the same 40 comprising a hand controlled shaft, a paper finger rod, paper finger devices thereon comprising rolls, an erasing plate, a rock shaft on said paper finger devices, clamping fingers on said rock shaft and coöperative 45 with said erasing plate, and connections between said rolls, said rock shaft and said hand controlled shaft, said connections comprising arms on said rock shaft connected with said rolls, a crank arm on said hand 50 controlled shaft and a link.

Signed at Marcellus, in the county of Onondaga, and State of New York, this 4th day of November, A. D. 1909.

HERBERT H. STEELE.
